[57] ABSTRACT

A centrifugal separator which includes a centrifugal pump for pumping the fluid from the separator, the pump being constituted by stationary vanes co-operating with the rotating fluid.

CENTRIFUGAL SEPARATOR

This invention relates to centrifugal separators.

According to the present invention a centrifugal separator for separating solid particles from fluid includes a centrifugal pump for removing the cleaned fluid from the separator.

Thus the pump may include stationary vanes mounted in relation to a rotatable casing and/or a rotatable shaft which is arranged to rotate the fluid so that centrifugal separation can be achieved and the rotary motion of the fluid in relation to the stationary vanes establishes the necessary pressure head for pumping the fluid from the separator.

A rotatable casing is conveniently mounted on an overhanging extension of a shaft so that the casing is capable of being slid off the free end of the shaft, and in this way it becomes an easy matter to remove, clean and replace the casing when it has collected a lot of particles.

One application of the invention is to the separation of the by-products from a magnesium water cell which continually gives off magnesium hydroxide in water. If the magnesium hydroxide can be separated off in the separator the water can be recirculated for continuous use in the cell.

The centrifugal separator can be used in a recirculating system for the fluid from a battery for driving an electric motor, and then the separator can be driven from the motor shaft. This is a particularly neat and compact arrangement where, for example, a magnesium water cell is used for driving an electric motor because the magnesium hydroxide can be easily separated before recirculation.

This is particularly advantageous for an electric motor for driving a lawn mower or a similar load.

The invention may be carried into practice in various ways and two embodiments will now be described by way of example with reference to the accompanying drawings, in which:

FIG. 1 is a cross-section through one form of separator,

FIG. 2 is a section on the line II—II in FIG. 1,

FIG. 3 is a section through III—III of another form of separator, and

FIG. 4 is a section on the line IV—IV in FIG. 3.

In the separator shown in FIG. 1 fluid containing particles which are required to be separated from the fluid is fed to a fluid supply pipe 20 extending through the wall 21 of a housing 22 which houses both an electric motor 23 and a rotary separator 24, the housing having a detachable end cover 19. The motor 23 has a shaft 25 journaled in bearings 26 in the housing 22, a hollow extension 27 of the shaft extending into the region within the cover 19.

Rigidly secured to a radial wall 29 in the casing 22 is a cylinder 28 co-axial with the shaft extension 27 and having at its end remote from the motor a diffuser 30 having vanes 31 best shown in FIG. 2. An outlet pipe 33 communicates with the interior of the cylinder 28. The rotary separator has a detachable cover 34 which defines with an end wall 35 carried on the cylinder 28 a filter chamber 36. The end wall 35 is provided with a rotary face seal between it and the cylinder 28. The cover 34 is secured by a screw 37 to the end of the extension shaft 27. Spring clips 38 are pivoted on the wall 35 so that the outer ends can clip over the end of the cover 34.

Fluid to be filtered enters the pipe 20 which leads across the interior of the cylinder 28 to within the hollow extension shaft 27 via radial bores 40. Lip seals 41 and 42 are provided to prevent fluid escaping. The fluid, which is supplied under a slight pressure, passes along the interior of shaft 27 and leaves it via radial exit openings 43 to pass into the chamber 36. The fluid and the solid particles are subjected to centrifugal forces and the solids collect on the walls of the cover 34, the cleaned

fluid being pumped out of the separator by means of the diffuser 30 and vanes 31 into the cylinder 28 and thence out of the fluid exit pipe 33.

When the cover 34 requires cleaning it can be removed by taking off the cover 19, by releasing a bayonet coupling 44, unscrewing the screw 37, and releasing the clips 38.

A rotor driven at about 3,000 r.p.m. by an electric motor might give the fluid sufficient angular momentum to co-operate with the stationary vanes 31 to give a pressure drop across the diffuser of 5, 6 or 7 lbs./sq. inch.

The diffuser vanes may not be as shown in FIG. 2 but could be in accordance with any known form of diffuser.

In the embodiment shown in FIGS. 3 and 4, the motor shaft 51 is solid and carries the removable, rotary separator casing 52 on its free end 53.

The end shield 54 of the motor carries an assembly consisting of a radial inlet 55, a tube 56 defining an inlet passage with the shaft 51, a tube 57 defining an outlet passage with the tube 56, and an outlet 58.

Diffuser vanes 59 are carried between annular flanges on the free ends of the tubes 56 and 57 for establishing a delivery pressure head in the rotating fluid and for pumping a small fraction of the fluid through openings 59 into a chamber 61, whence the fluid is forced through radial openings 62 to provide hydro-dynamic lubrication to a bearing consisting of co-operating cylindrical surfaces on respective parts 63 and 64 of the stationary and rotary components. A seal 65 protects against loss of fluid from the chamber 61.

The stationary external flange 66 on the tube 56 assists the flow of fluid centrifugally outwards and back through the diffuser.

The casing 52 can be easily detached at 67 and 53, and removed for cleaning or replacement.

A cover (not shown) releasably fitted to the motor and shield will protect the rotating parts and keep dirt off. It will have openings for inlet and outlet fluid lines.

Each embodiment is suitable for filtering off the magnesium hydroxide by-products from the potassium bromide catalyst in a magnesium/water electric cell for driving a motor for a lawn mower. The same motor will of course be the one driving the separator.

What we claim as our invention and desire to secure by Letters Patent is:

1. A centrifugal separator for separating solid particles from fluid, the separator including a rotatable casing for rotating the fluid and defining a chamber for the fluid, the casing having a first end and a second end, a rotatable shaft passing through the first end of the casing and fixedly attached at one end to the second end of the casing, an inlet for fluid, said inlet being coaxial with said shaft, a centrifugal pump operatively associated with said chamber for removing cleaned fluid from the casing, said pump comprising stationary vanes for co-operation with rotating fluid and an outlet co-axial with said shaft.

2. A separator according to claim 1 wherein said shaft is hollow and has apertures formed adjacent the second end of said casing, said shaft defining said inlet for fluid.

3. A separator according to claim 1 wherein said inlet for fluid is formed between said shaft and said outlet.

4. A separator according to claim 1 wherein said casing includes means sealing the casing from the second end of the shaft.

5. A separator according to claim 1 wherein said pump is situated within said casing.

UNITED STATES PATENT OFFICE
CERTIFICATE OF CORRECTION

Patent No. 3,666,170 Dated May 30, 1972

Inventor(s) ANTONIO CACCIABUE, and RODNEY THOMAS BEAZLEY

It is certified that error appears in the above-identified patent and that said Letters Patent are hereby corrected as shown below:

The claim for priority as evidenced by the claim filed March 10, 1972 of British applications 21880/68 and 51107/68 should appear in the issued patent.

Signed and sealed this 26th day of September 1972.
